TRAY

David Douglas, Manitowoc, Wis., assignor to East Wisconsin Trustee Company of Manitowoc, Manitowoc, Wis., a corporation of Wisconsin

Filed Oct. 19, 1965, Ser. No. 87,599

Term of patent 14 years

(Cl. D44—10)

FIG. 1 is a top plan view of a tray showing my new invention;

FIG. 2 is a sectional view taken along line 2—2 of FIG. 1; and

FIG. 3 is a sectional view taken along line 3—3 of FIG. 1.

The essential feature of my design resides in the particular configuration of the peripheral edges in combination with a substantially rectangular well portion.

I claim:

The ornamental design for a tray, substantially as shown and described.
